UNITED STATES PATENT OFFICE.

ALBERT A. GORDON, JR., OF WORCESTER, MASSACHUSETTS, ASSIGNOR
TO CROMPTON & KNOWLES LOOM WORKS, A CORPORATION OF MAS-
SACHUSETTS.

BRAKE MECHANISM OF LOOMS.

No. 810,113.

Specification of Letters Patent.

Patented Jan. 16, 1906.

Application filed February 27, 1905. Serial No. 247,417.

To all whom it may concern:

Be it known that I, ALBERT A. GORDON, Jr., a citizen of the United States, residing at Worcester, in the county of Worcester and 5 State of Massachusetts, have invented certain new and useful Improvements in Brake Mechanism of Looms, of which the following is a specification.

My invention relates to brake mechanism, 10 and more particularly to the brake mechanism of looms.

The object of my invention is to improve upon the ordinary construction of the mechanism for operating the brake of a loom and 15 to provide mechanism for conveniently and effectively releasing the brake from the brake-wheel when the loom is stopped and it is desired to turn the loom by hand.

My invention consists in certain novel features of construction of my improvements, 20 as will be hereinafter fully described.

I have only shown in the drawings a detached portion of a brake mechanism of a loom embodying my improvements sufficient 25 to enable those skilled in the art to understand the construction and operation thereof.

Referring to the drawings, Figure 1 is an end view of a loom-frame, showing the 30 brake-wheel on the main shaft of the loom and a brake-lever with my improvements combined therewith. Fig. 2 shows, on an enlarged scale, some of the parts at the left in Fig. 1 detached looking in the direction of arrow *a*, same figure. Fig. 3 shows the parts 35 shown in Fig. 2 in a different position. Fig. 4 shows the parts shown in Fig. 3 in a different position. Fig. 5 is a section on line 5-5, Fig. 3, looking in the direction of arrow *b*, same figure. Fig. 6 is an end view of a modified construction of my improvements applied to a different form of shipper-lever 40 looking in the direction of arrow *c*, Fig. 7. Fig. 7 is a side or edge view of the parts shown 45 in Fig. 6 looking in the direction of arrow *d*, same figure. Fig. 8 corresponds to Fig. 6, but shows some of the parts in a different position; and Fig. 9 corresponds to Fig. 8, but shows some of the parts in a different position. Figs. 2 to 9, inclusive, are shown on an 50 enlarged scale.

In the accompanying drawings, referring to Figs. 1 to 5, inclusive, 1 is the loom side or frame. 2 is the main or crank shaft. 3 is a

brake-wheel fast on said shaft. 4 is the 55 brake-lever pivoted on a pin 5 and having the brake-surface 4' thereon adapted to engage the periphery of the brake-wheel 3. The opposite end of the brake-lever 4 has attached thereto the upper end of a tension-spring 6. The lower end of said spring is attached to a stand 7. On the end of the 60 brake-lever 4 is a side extension or ear 4'', through which loosely passes the lower end of a vertically-moving connector 8. On the 65 lower end of the connector 8 is an adjusting-nut 9, adapted to engage the under side of the ear 4''. The upper end of the connector 8 is pivotally attached to a lever 10, in this 70 instance by a hooked end 8', (see Fig. 5,) extending through an opening in said lever. The lever 10 has a hub 10' at its lower end, which is pivotally mounted on a stud 11, secured to a stationary bracket or stand 12. (See Fig. 5.) The upper end of the lever 10 75 extends above the slotted guide-arm 13 for the shipper-lever 14 and has a side horizontal extension 10'' thereon, (see Fig. 1,) which extends across the pathway of and is adapted to be engaged by the shipper-lever 14. The 80 upright part of the lever 10 has a bearing for a rocking pin or shaft 15. Secured on one end of said rocking pin 15 is the hub 16' of a cam-arm 16, which is adapted to extend within a recess 13' in the shipper-lever 85 guide-arm 13 and to engage a shoulder 13'' at the outer end of said recess. (See Fig. 3.) On the opposite end of the rocking pin 15 is secured, in this instance by a set-screw 17, the hub 18' of an arm 18, having a horizontally-extending side projection 18'', (see Fig. 5,) forming a handle or engaging end. On the inner side of the hub 18' of the arm 18 is a lug or projection 18''', which extends in the path of and is adapted to engage two lugs or 90 projections 10''' on the central portion of the lever 10. The engagement of the lug 18''' with the projections 10''', as shown in Figs. 2 and 3, limits the rocking movement of the pin 15, and consequently of the cam-arm 16 95 and the arm 18.

The operation of my improvements (shown in Figs. 1 to 5, inclusive, and above described) will be readily understood by those skilled in the art. When the loom is at rest and it is 105 not desired to turn the loom by hand, the parts may remain as shown in Figs. 1 and 2 with the brake-lever engaging the brake-

wheel through the action of the spring 6. When it is desired to release the brake-lever to turn the loom by hand, the engaging end 18" on the arm 18 is raised. The raising of 5 the arm 18, fast on the rocking pin or shaft 15, causes said shaft to rock, and with it the cam-arm 16. The outer end of the cam-arm 16 will engage with the shoulder 13" on the shipper-lever guideway 13, and the lug 18" 10 on the hub 18' of the arm 18 coming into engagement with the lug 10" on the lever 10 will rock said lever 10 and move it from the position shown in Fig. 2 to the position shown 15 in Fig. 3. The movement of the lever 10 through connector 8 and nut 9 will raise the outer end of the brake-lever 4 against the action of the spring 6 and disengage the brake end 4' from the brake-wheel 3 to leave said wheel free to rotate. The shape of the 20 engaging end of the cam-arm 16 is such that when the parts are in the position shown in Fig. 3 said end, in connection with the shoulder 13", acts as a lock to prevent any accidental displacement of the parts and the application 25 of the brake on the brake-wheel. It will be understood that the adjustable nut 9 on the lower end of the connector 8 is in such a position on said connector, relative to the lug 4" on the brake-lever 4 when the brake is on the 30 brake-wheel that there will be a space between said nut 9 and the lug 4", as shown in Fig. 2, so that the spring 6 may exert its full tension on the brake-lever to operate the same. When it is desired to start the loom and the shipper-lever 14 is moved into its upright position 35 from the position shown in Fig. 2, said shipper-lever comes in contact with the horizontally-projecting end 10" on the lever 10 and moves or rocks said lever inwardly and carries with it the arm 18 and the cam-arm 16, 40 causing the end of the cam-arm 16 to be disengaged from the end 13" of the recess 13', and allows said cam-arm 16 and the arm 18 to drop down by gravity into the position 45 shown in Fig. 4. When the loom is stopped, the shipper-handle is moved outwardly from the position shown in Fig. 4 to the position shown in Fig. 2. The lever 10 through the 50 action of the spring 6 is immediately moved back into the position shown in Fig. 2, allowing the spring 6 to act on the brake-lever 4 and apply the brake 4' to the brake-wheel 4, all as will be fully understood by those skilled 55 in the art.

Referring to Figs. 6, 7, 8, and 9, I have shown in said figures a modified construction of my improvements applied to a brake mechanism having a different form of shipper-lever. In said figures, 1 is the loom side 60 or frame. 19 is the shipper-lever, having a hub 19' pivotally mounted on a stud 20 and having a handle portion 19". The lower end of the shipper-lever 19 carries a pin 21, which extends into an elongated slot 22' in the upper 65 part of a lever 22, the hub 22" of which is

pivotedly mounted on a pin 23. The lower part of the lever 22 is made forked to receive the end of a rod or connector 24 to the driving-belt pulley (not shown) of the loom. The lever 22 has a side extension 22'" thereon, the lower edge of which is adapted to engage the upper end 25' of a stand 25. A spiral spring 25" is attached at one end to the lower end of the stand 25 and at its other end to the outer end of the projection 22'". 70 Pivotally mounted on the stud 20, outside of the hub 19' of the shipper-lever 19, is a hub 26' of a lever or arm 26, the upper free end of which is adapted to engage and rest against a projecting part of the shipper-lever 19. (See 80 Figs. 7 and 9.) Extending out from the hub 26' of the lever 26 is a projection 26", to which is pivotally connected the upper end of the connector or link 27. The lower end of said connector or link 27 extends loosely 85 through an opening in the end of a brake-lever 28. On the lower end of the connector 27 is threaded an adjustable nut 29. A spiral spring 30 is attached at its upper end to the 90 brake-lever 28 and at its lower end to a stationary part. (Not shown.) The brake-lever 28 (only the end of which is shown) may be of the same construction and operation as the brake-lever above described. The upright arm or lever 26 carries a rocking-pin 31. 95 Fast on one end of said pin is the hub 32' of an arm 32, having thereon a handle or knob 32". On the opposite end of said pin 31 is fast a cam-arm 33, the free end of which is adapted to engage a stationary projection 34 on the 100 frame. The downward movement of the arm 32 and the cam-arm 33 is limited by the engagement of a projection on the inner end of the arm 32 with the front edge of the lever 26, and the upward movement of the arm 32 105 and cam-arm 33 is limited by the engagement of the arm 32 with an extension 26'" on the arm 26. The shape of the projection 34 is such that it acts to prevent any accidental movement of the cam-arm 33. (See Fig. 8.) 110 The shipper-lever 19 has a projection 19'" on its inner side and is adapted to be engaged by the end of a stop-motion lever 35, supported on the under side of the breast-beam 15 in the ordinary way. A stop-motion lever 36, 115 pivoted on a bolt 37 on the upper side of the breast-beam, extends in the path of and is adapted to be engaged by the shipper-lever 19 in the ordinary way.

When the loom has been stopped and the 120 brake is in contact with the brake-wheel, as shown in Fig. 1, the several parts of the mechanism just described will be in the position shown in Figs. 6 and 7. When it is desired to release the brake, the arm 32 is moved upward, by means of the knob 32", to rock the pin 31, and with it the cam-arm 33. The free end of the cam-arm 33 comes in contact with the projection 34, and the arm 32, 125 engaging the projection 26'" on the lever 26, 130

rocks and moves backwardly said lever, as shown in Fig. 8, and through connector 27 raises the brake-lever 28 against the action of the spring 30 to release the opposite 5 end of the brake-lever from the brake-wheel, as above described in connection with Figs. 1 to 5. When the shipper-lever 19 is moved to start the loom, it comes in contact with the upper end of the lever 26 and moves said 10 lever backwardly and disengages the end of the cam-arm 33 from the stop 34, allowing said cam-arm 33 and the arm 32 to drop down by gravity into the position shown in Fig. 9. When the cam-arm 33 is moved into 15 the position shown in Fig. 9, it cannot come in contact with the projection 34 when the shipper-lever 19 is moved to stop the loom, and the spring 30 will act to operate the brake-lever to apply the brake and through 20 link 27 to move the lever 26 into the position shown in Fig. 6.

The advantages of my improvements will be readily appreciated by those skilled in the art. They are of simple construction and 25 may be adapted to be applied to and used in connection with the ordinary form of brake mechanism employed on looms to release the brake after the loom is stopped and allow the turning of the loom by hand, and when the 30 loom is started the parts of the mechanism are automatically operated to allow of the automatic applying of the brake when the loom is again stopped.

It will be understood that the details of 35 construction of my improvements may be varied, if desired.

Instead of having the movable arms 16 and 33 provided with cam-surfaces they may be made without them and the stationary 40 parts 13" and 34 be made with cam-surfaces and the same results obtained, as will be readily understood.

Having thus described my invention, what I claim as new, and desire to secure by Letters Patent, is—

1. In a loom, mechanism for releasing the 45 brake from the brake-wheel independently of the shipper-lever, said mechanism comprising a pivoted lever connected with the brake-lever, and said brake-lever, an arm 50 carried on said pivoted lever and adapted to engage a stationary part, which part acts to hold said arm from accidental movement, and means for moving said arm to cause it to engage said stationary part, the engagement 55 of said arm with the stationary part causing the movement of the pivoted lever and the release of the brake from the brake-wheel.

2. In a loom, the combination with mech- 60 anism for releasing the brake from the brake-wheel independently of the movement of the shipper-lever, said mechanism comprising a pivoted lever connected with the brake-lever, and said brake-lever, a rocking cam-arm car- 65 ried on said pivoted lever, and having a cam- surface thereon, and adapted to engage a sta- tionary part, which part acts to hold said cam-arm from accidental movement, and means for moving said cam-arm to cause it to engage said stationary part, the engage- 70 ment of said cam-arm with said stationary part causing the movement of said pivoted lever and the release of the brake from the brake-wheel, of the shipper-lever adapted to engage and move said pivoted lever when 75 said shipper-lever is moved to start the loom, and to hold the brake released from the brake-wheel, and release the cam-arm and allow it to return to its inoperative position.

ALBERT A. GORDON, JR.
